DESIGN FOR A PIANO LEG

Eric Gugler, New York, N. Y., assignor to Steinway & Sons, New York, N. Y., a corporation of New York

Application December 17, 1938, Serial No. 81,857

Term of patent 14 years

To all whom it may concern:

Be it known that I, Eric Gugler, a citizen of the United States of America and residing at 134 East 40th Street, New York city, in the county and State of New York, have invented a new, original, and ornamental Design for a Piano Leg, of which the following is a specification, reference being had to the accompanying drawing, forming part thereof.

I claim:

The ornamental design for a piano leg, substantially as shown.

ERIC GUGLER.
